William J. Prevost

UNITED STATES PATENT OFFICE.

WILLIAM J. PREVOST, OF SPRINGFIELD, MASSACHUSETTS.

MATCH-BOX.

1,340,980.

Specification of Letters Patent.

Patented May 25, 1920.

Application filed September 9, 1919. Serial No. 322,755.

To all whom it may concern:

Be it known that I, WILLIAM J. PREVOST, a citizen of the United States of America, residing at Springfield, in the county of 5 Hampden and Commonwealth of Massachusetts, have invented certain new and useful Improvements in Match-Boxes, of which the following is a specification.

This invention relates to match containers, and aims to provide a compact container having an outlet at the bottom through which the finger may be conveniently inserted to lift a single match at a time. I provide additional means by which 15 the matches within the container are forced and guided toward said outlet.

Another object of my invention is to provide for said match container a door of unique construction, which, when closed, retains the stack of matches within the chamber and yet permits them to pass in narrow file through a small outlet at the bottom.

Another object is to provide, as an alternative for the door, a retaining device in the 25 form of a shutter slidable vertically. These and other objects will become apparent from the description below.

Referring to the drawings, Figure 1 is a cross-sectional elevation of the first form of 30 my device, showing its essential features.

Fig. 2 is a front elevation of the same.

Fig. 3 is a rear elevation of the same.

Fig. 4 is a front elevation of the second form of my device.

Fig. 5 is a cross-sectional elevation of the 35 device disclosed in Fig. 4, showing the way an uncovered box of matches is inserted to fill the container.

In the description below characters of reference refer to like-named parts on the drawings.

The base of the container is shown at 1; 2 represents the side walls, and 3 the inclined top. An inclined partition 4 separates the 45 chamber thus provided into a front and rear compartment 5 and 6 respectively, the former containing and guiding the matches 7 in the manner to be described. The bottom of the chamber 5 is provided with a 50 channel 8, extending rearward of the outlet; this permits insertion of the finger to grasp a match. An additional inclined wall 9 further guides the matches toward the outlet.

55 A door 10, pivoted in the side walls at 11, retains the matches in the chamber 5; said

door is provided with slots 12 and 13 through which the finger may be inserted and through which the height of the pile of matches may be observed at any time. A 60 space is provided between the lower end of the door 10 and the bottom of the chamber 5, through which the matches pass from the chamber. Suitably secured bent rods are provided at this outlet to permit but a single 65 match to pass at one time. An inverted U-shaped rod 14, of a width about equal to that of the channel 8, is secured at, and extends upright from, the bottom of the chamber 5. A rod 15, curved as shown, is 70 secured in the side walls 2 and extends across the outlet. A second inverted U-shaped rod 16, of greater width than the first and extending above the same, is secured at the bottom of the chamber 5. Thus, on passing 75 under the door 10, the matches are guided upward successively by the rods 14 and 15, and are ultimately removed by being caught between the finger and the rod 16.

The partition 4 is slotted at 17 to receive 80 the pin-like projection 18 of the depressing member 19. This latter member extends over the interior cross-sectional area of the chamber 5, and presses upon the pile of matches and forces them toward the outlet. 85 A spring 20 is secured at one end to the base 1, at the other to the block 21 secured to the pin 18 in the rear compartment 6. Said block 21 provides an additional guide to the member 19 in its motion up and down the 90 chamber 5. A rear door 22 is hinged at 23 in the side walls 2 of the container; this door permits of access to the rear compartment 6 and the mechanism contained therein. A removable pin 24 passes through a side 95 wall 2 into a suitable hole in the door 10 to lock the latter when closed; a similar provision may be made to lock the rear door. A finger hole 25 is contained in the rear door, this hole may also be used to secure the device to a wall. On each side of the container, in the shoulder formed by the base 1 and the side walls 2, is a block 26 having a roughened upper surface upon which the match may be struck.

100 Figs. 4 and 5 show an alternative construction of my container. The frame consists of a back 27 having a hole therein through which the device may be secured to a wall. The side walls are shown at 28; the undersurface 110 29 is flat, so that the device may be used portably. The bottom of the interior of the

chamber 30 is inclined so that the matches 31 will move, by gravity, toward the outlet. A fence 32, provided with a finger-slot 33, extends outward and upward from the bottom to retain the matches at the outlet. The top 34 of the container is slotted transversely to permit the shutter 35 to slide vertically through it. Vertical slots 38 on the interior of the side walls provide additional guides 5 for the shutter. A shoulder at the bottom of each guide 38 limits the lower position of the shutter so that a sufficient space is provided for the matches to pass. Said shutter retains the matches within the chamber; to replenish 10 the supply, the shutter is lifted. Finger-slots 36 and 37 are cut into the shutter 35, they also serve as gages for observing the height of the matches within the chamber. A roughened surface 39, upon which the 15 matches are struck, is provided on the upper projection of the shutter.

An important feature of my invention consists in forming and hanging or slidably mounting the door of my match safe so that 20 an uncovered full box of matches may be entered within the door opening for the purpose of filling the match box. Fig. 5 shows an uncovered box of matches 40 in position with the door 35 raised, to replenish the supply 25 in the container.

I claim:

1. A match container mounted on a base, comprising two chambers separated by a slotted partition, one of said chambers adapted to hold the matches and having an outlet at the bottom, sloping interior walls con- 30

verging toward said outlet, a substantially flat plate slidable lengthwise of said first named chamber, said plate having a pin projecting through the slot in said partition into 40 said second named chamber, means to force said plate against the matches comprising a spring secured at one end to said pin and at the other end to said base, and match-striking surface thereon. 45

2. A container for matches having in combination, an inclosed chamber portion to receive the matches, the front side of the container comprising a door member which is pivotally secured at its lower end to permit the upper end of the same to open for the purpose of discharging the contents of a full box of matches face front, as described, into the container having a fixed discharge outlet for the matches at its lower end, fixed wires extending across the outlet to permit only one match at a time to be removed by the hand of the operator, said wires serving to hold back the remainder of the matches in the container. 50

3. A match container having in combination, an inclosed chamber to receive the matches, the chamber having an inclined floor portion to direct the matches downward and an outlet opening for the matches at the lower end of the floor, an obstruction in front of the opening, but spaced therefrom to permit the removal of the matches from the outside of the container, said chamber having a movable front portion to receive the supply for refilling purposes. 55

WILLIAM J. PREVOST. 60
